Specification for Design.

Patented Sept. 2, 1913.

Application filed July 10, 1913. Serial No. 778,385. Term of patent 3½ years.

● *To all whom it may concern:*

Be it known that I, ALFRED J. FLAUDER, a subject of the Emperor of Austria-Hungary, and resident of Bridgeport, in the county of Fairfield and State of Connecticut, have invented a new, original, ornamental, and colonial Design for a Clock-Case, of which the following is a specification, reference being had to the accompanying drawings, forming part thereof.

In the drawings: Figure 1, shows a front elevation of my new design of clock-case. Fig. 2, is a plan view of the same. Fig. 3,

illustrates a rear view of the case, and Fig. 4, shows a side or edge view, both of which are alike in ornamentation.

I claim:

The ornamental design for a clock case as shown.

Signed at Bridgeport in the county of Fairfield and State of Connecticut this 28th day of June, 1913.

ALFRED J. FLAUDER.
